PAPERMAKER'S FELT

Howard M. Helland, Newfane, N.Y., assignor to
Lockport Felt Company, Newfane, N.Y.

Filed May 6, 1959, Ser. No. 811,421

7 Claims. (Cl. 28—78)

This invention relates to a structurally improved papermaker's felt, such as for use for example in the manufacture of paper, paper board, pulp, and similar items such as for example asbestos shingles, Transite pipes, and like products. More specifically, the invention relates to improvements in the art referred to in my previously filed applications Serial No. 743,624, filed June 23, 1958, and Serial No. 756,405, filed August 21, 1958.

It is a primary object of the present invention to provide an improved papermaker's felt constructed of any of the conventionally used grades of wool, cotton, or other natural or synthetic fibres or combinations thereof; so fabricated as to provide a papermaker's felt which at the same time possesses optimum lateral balance and resistance to longitudinal curl, and is of "high bulk" characteristics.

Another object of the invention is to provide a felt as aforesaid which presents a smooth working surface of improved pulp supporting and cushioning characteristics.

Another object is to provide a felt as aforesaid which is efficient as a drainage filter in its intended use.

Still another object is to provide an improved felt as aforesaid which is of desirable strength in the direction of the felt load and which also inherently possesses improved dimensional stability characteristics.

Other objects and advantages of the invention will appear from the specification hereinafter, and the accompanying drawings wherein:

Fig. 1 is a diagrammatic perspective view of one form of plied yarn such as may be employed in construction of a felt of the present invention;

Fig. 2 is a plan view (at reduced scale) of a laterally distorted swatch of fabric, illustrating the braid pattern employed in the manufacture of the felt, the yarns being shown as variously colored to facilitate reading the drawing;

Fig. 3 is a plan view corresponding to Fig. 2 but of a swatch of the fabrication as it actually appears subsequent to initial braiding thereof; and

Fig. 4 is a diagrammatic fragmentary sectional view taken along line IV—IV of Fig. 2.

In the papermaker's wet felt art it is a prime object to provide a fabric structure which is of "high bulk" characteristics yet longitudinally strong, comprising an efficient water-drainage or filter membrane. For such purposes the wool and/or other fibres used must be so integrated as to present to the pulp being treated a uniformly smooth and level yet resilient surface. The present invention provides the above stated objects through use of a novel fabrication of yarns whereby the individual fibres subsequent to the yarn interlocking operation remain free to move relative to one another during the fabric "fulling" or milling operations.

This effect is obtained by employing an interlock pattern involving only generally parallel warp yarns which are intertwined in novel manner. Preferably, at least a large percentage of these yarns will be of such form that the fibres thereof are substantially untwisted, as com-

2

pared to conventionally twisted fibre yarns as are usually employed in this art. The yarns may be either of the so-called woolen system or any of the so-called worsted systems, and may be either "singles" or "plied" yarns.

5 In fabricating a felt of the present invention either a "singles" yarn or a conventional "plied" yarn may be employed. Or, as still another alternative, as a separate operation, a plurality of "singles" yarns made with a minimum "singles" twist such as the pair of yarns 10 10—12 shown in Fig. 1 may be plied as by means of a neutralizing Z twist. Hence, the resultant plied yarn designated generally at 14 comprises intertwined singles yarns, the individual fibres of which are as near as possible untwisted. By way of a specific example, the card 15 roping may be initially drafted and S twisted at the rate for example of 4.0 t.p.i. (twists per inch), depending upon the fibre lengths and other variables. The two singles yarns so produced may then be relatively entwined by means of a neutralizing Z twist in such manner as to 20 provide a plied yarn for example of 4.5 t.p.i. Approximately this ratio of singles and plied yarn twists will result in production of a plied yarn as indicated at 14 in the drawing wherein the individual fibres are only very slightly twisted (in one direction or the other) or are 25 substantially untwisted about their own axes, while gently winding spirally about the neutral axis of the yarn.

In the alternative, the card roping may be initially formed into singles yarn stock by means of a Z twist operation, and the singles yarns may thereupon be S 30 twisted into plied yarn form, to provide the plied yarn stock 14 as explained hereinabove. In either case the yarn stock may be described as comprising two groups of untwisted fibres gently rolling around one another. Due to the fact that the singles yarns are relatively entwined the overall structure of the plied yarn 14 has 35 adequate strength to withstand the subsequent braiding operation, in spite of the fact that the individual fibres are substantially untwisted.

As the second step in the manufacture of the felt of 40 the present invention, pluralities of the yarns 14 are intertwined as shown in Fig. 2. The construction is illustrated herein as when being laterally stretched out of its natural "set" condition, to facilitate understanding the nature of the yarn interweaving system. When the structure 45 is relaxed its longitudinal resiliency causes it to return to its normal condition as shown in Fig. 3 and it will be noted that the yarns 14 are interlinked and nested together in a manner quite unique in the wet felt art. Each plied yarn member of the system runs generally 50 longitudinally of the belt into which the fabric is made, although it follows a slightly zig-zag course. To facilitate reading the drawing some of the yarns are darkly colored as indicated at 16 in Figs. 2, 3. It will be seen that along each leg of the zig-zag course each yarn passes 55 first over two adjacent yarns and then reverses course and passes under the same two yarns. It then reverses course again and passes over the same two yarns, but then continues on the same course and passes under two more yarns. It then reverses course and passes over the 60 two last mentioned yarns, whereupon it reverses again and passes under the two last mentioned yarns; and so on throughout the length of the fabrication. In my prior application Serial No. 743,624 referred to hereinabove, each yarn passes either over or under all of the adjacent 65 yarns throughout each leg of its zig-zag course, and in application Serial No. 756,405 each yarn passes first over two yarns and then under two yarns, and then reverses course and passes under two yarns and then over, and so on. Thus the constructions are substantially different. 70 Subsequent to braiding, the fabric is submitted to any suitable shrinking and "fulling" or "milling" operations; and thus the fabric is shrunk and "fullled" as into the

form illustrated by Figs. 3-4. As shown in Fig. 3, the yarns 14 are substantially straightened out in plan view to their conditions of maximum efficiency with respect to resistance to tension loads on the felt. It will of course be understood that the fabric of the invention may be constructed by any suitable type machine.

Whereas, the yarns 14, due to their relatively entwined positions in the interlock pattern acquire optimum felt tension resistance characteristics, the locally soft nature of the yarn stock permit them to easily deform and bulk out and respond in improved manner to the fulling treatment because the individual fibres thereof are of improved mobility. Hence, in the resulting felt fabrication the fibres provide a mat of superior surface smoothness and cushioning characteristics. At the same time the double thickness and laterally unrestrained nature of the interlock pattern permits the fabric to "breathe" and to operate with maximum efficiency in accord with the phenomenon of capillarity and in response to the "pumping" action within the felt when passing through compression rolls; thereby improving its water removing abilities. For the same reason the fabric is of improved inherent self-cleaning characteristics and is more responsive to conventional cleaning devices than are felts of other construction. Thus, each fibre of the fabrication is disposed to act more efficiently in its assigned task.

By virtue of the more efficient bulking of the fibres in the felt of the invention, it is of superior surface or "finish" characteristics. It is a feature of this invention that in the finished felt belt the individual yarns and fibres are disposed at angles only slightly oblique to the direction of belt travel (Fig. 3); thereby providing a felt of increased total load pulling power for the same felt weight, and avoiding "head-on" impacts of yarn "rises" or "floats" against stationary equipment such as suction boxes, cleaning shoes, etc.

It is a particular feature of the present invention that by virtue of the braid pattern of the yarns a "belt" (such as a papermaker's "felt") made from this fabric is laterally "balanced" and does not tend to curl up in the direction of its yarns. Hence, the "felt" is inherently balanced and tends to ride true on the rollers of the paper making machine. At the same time the fabric yarns retain their optimum bulk characteristics, as explained hereinabove. Thus, it will of course be appreciated that the invention is not limited to the precise construction illustrated herein nor to the specific "wet" felt usage described hereinabove, and that the construction may be modified such as for example by interlacing each yarn any other desired number of times with adjacent yarns along each "short" general course before reversing course into a "long" general course, without departing from the spirit of the invention or the scope of the appended claims.

I claim:

1. A new papermaker's felt belt for supporting and draining paper making material, said belt comprising a felt-like fabric structure having only substantially untwisted yarns running generally parallel and lengthwise of the belt with adjacent yarns interlocked by means of a braiding pattern disposing each yarn member to follow a slightly zig-zag course lengthwise of the belt, each yarn member passing along each leg of the zig-zag course first over two adjacent yarns of adjacent courses, and then reversing to pass under the same two yarns; again reversing course and passing over the same two yarns and then passing under paired adjacent yarns while continuing on the same course, whereupon it again reverses course and repeats the aforesaid pattern, the individual fibres of said yarns being spirally wound but substantially untwisted about their own axes, said yarns each comprising card roping twisted only slightly into twisted yarn form, said fabric being fulled.

2. A new papermaker's felt belt for supporting and draining paper making material, said belt comprising a felt-like fabric formed solely of relatively soft twisted

5

yarns running lengthwise thereof in side-by-side relation and interlocked by means of a braiding pattern disposing each yarn member to follow a slightly zig-zag course lengthwise of the belt, each yarn member passing along each leg of the zig-zag course first over two adjacent yarns of adjacent courses, and then reversing to pass under the same two yarns; again reversing course and passing over the same two yarns and then passing under paired adjacent yarns while continuing on the same course, whereupon it again reverses course and repeats the aforesaid pattern, the individual fibres of said yarns being substantially untwisted about their own axes, said fabric being fulled.

3. A new papermaker's felt belt for supporting and draining paper making material, said belt comprising a felt-like structure having only substantially untwisted plied warp yarns running generally parallel and lengthwise thereof with adjacent yarns interlocked by means of a braiding pattern disposing each yarn member to follow a slightly zig-zag course lengthwise of the belt, each yarn member passing along each leg of the zig-zag course first over two adjacent yarns of adjacent courses, and then reversing to pass under the same two yarns; again reversing course and passing over the same two yarns and then passing under paired adjacent yarns while continuing on the same course, whereupon it again reverses course and repeats the aforesaid pattern, the individual fibres of said yarns being spirally wound but substantially untwisted about their own axes, said plied yarns each comprising a pair of singles yarns each comprising card roping twisted into conventional S twisted yarn form and Z twisted together in opposite direction into plied yarn form, said interlocked yarns being fulled.

4. A new papermaker's fabric belt for supporting and draining paper making material, said belt comprising a felt-like structure having relatively soft twisted warp plied yarns running lengthwise thereof in side-by-side relation and interlocked by means of a braiding pattern disposing each yarn member to follow a slightly zig-zag course lengthwise of the belt, each yarn member passing along each leg of the zig-zag course first over two adjacent yarns of adjacent courses, and then reversing to pass under the same two yarns; again reversing course and passing over the same two yarns and under paired adjacent yarns while continuing on the same course, whereupon it again reverses course and repeats the aforesaid pattern, the individual fibres of said yarns being substantially untwisted about their own axes, said yarns each comprising a pair of singles yarns twisted together into plied yarn form, said fabric being fulled.

5. A new papermaker's felt fabric for supporting and draining paper making material, said fabric comprising a structure of relatively soft-twisted plied yarns running lengthwise thereof in side-by-side relation and interlocked by means of a braiding pattern disposing each yarn member to follow a slightly zig-zag course lengthwise of the fabric, each yarn member passing along each leg of the zig-zag course first over adjacent yarns of adjacent courses, and then reversing to pass under the same two yarns; again reversing course and passing over the same two yarns and under paired adjacent yarns while continuing on the same course, whereupon it again reverses course and repeats the aforesaid pattern, said yarns having their individual fibres substantially untwisted about their own axes and each comprising a pair of singles yarns S twisted together into plied yarn form, each of said single yarns comprising card roping Z twisted in opposite direction into singles yarn form, said fabric being fulled.

6. A papermaker's felt for supporting and draining paper making material, said felt comprising a fabric structure having plied yarns running lengthwise thereof in side-by-side relation and interlocked by means of a braiding pattern disposing each yarn member to follow a slightly zig-zag course lengthwise of the belt, each

yarn member passing along each leg of the zig-zag course first over adjacent yarns of adjacent courses, and then reversing to pass under the same two yarns; again reversing course and passing over the same two yarns and under paired adjacent yarns while continuing on the same course, whereupon it again reverses course and repeats the aforesaid pattern, said yarns each comprising a plurality of singles yarns twisted together into plied yarn form, each of said singles yarns comprising card roping twisted into yarn form, said fabric being fulled.

7. A new papermaker's felt for supporting and draining paper making material, comprising a fabric structure having only warp yarns, said warp yarns running lengthwise of the fabric and in side-by-side relation, each warp yarn being interlocked alternately with yarns adjacent thereto by means of a braiding pattern disposing each yarn member to follow a slightly zig-zag course lengthwise of the belt, each yarn member passing along

each leg of the zig-zag course first over adjacent yarns of adjacent courses, and then reversing to pass under the same two yarns; again reversing course and passing over the same two yarns and under paired adjacent yarns while continuing on the same course, whereupon it again reverses course and repeats the aforesaid pattern, said fabric being fulled.
